United States Patent Office.

IMPROVED LUBRICATOR.

T. R. ROBINSON, AND R. E. JONES, OF PROVIDENCE, RHODE ISLAND.

Letters Patent No. 60,251, dated December 4, 1866.

SPECIFICATION.

TO ALL WHOM IT MAY CONCERN:

Be it known that we, THOMAS R. ROBINSON, and ROYAL E. JONES, of Providence, in the county of Providence, in the State of Rhode Island, have invented a new and useful improvement in Lubricating Bolsters for spinning frames, and Lubricator for other machinery, for the purpose of regulating the flow of oil; and we do hereby declare that the following is a full and exact description thereof, reference being had to the accompanying drawings, and to the letters of reference marked thereon.

Figure 1 is a perspective view.

Figure 2 is a sectional view of the bolster.

Figure 3 is a perspective and sectional view of the cap or press-screw used on the "lubricator for other machinery;" the only difference between the cap or press-screw used on the bolster, and the cap or press-screw used on the lubricator for other machinery, being that in the latter no "spindle hole" is drilled.

The nature of our invention consists in regulating the flow of oil in a bolster and lubricator for other machinery, by the use of a press-screw, which compresses an absorbent placed in the bottom of an annular chamber, as shown in the drawings, (fig. 2,) and as hereafter described.

To enable others skilled in the art to make and use our invention, we will proceed to describe the construction and operation.

A is an annular chamber for holding the supply of oil. B is the absorbent placed in the bottom of the chamber A, and is compressed to regulate the flow of oil. C is the cap or press-screw, the cylinder of which extends into the chamber A, and presses upon the absorbent B. This cylinder also forms the inner boundary of chamber A, and is surrounded by the oil. D D are the holes in the top of the press-screw C, for admitting the oil to the chamber A. E E is the chamber in which the spindle revolves, and into which the oil flows. When used as a bolster, a hole must necessarily be drilled in the press-screw C, as shown in fig. 2, for receiving the spindle; but when used for lubricating other journal bearings than those of spindles, the cylinder of the press-screw is made solid, that is, no "spindle passage" is drilled, as shown in fig. 3.

The operation is as follows: The absorbent is placed in the bottom of the chamber A, and the press-screw is then screwed down upon it. The chamber A is then filled with oil, through the holes D D. The flow of oil is regulated by the press-screw, more or less compression being used according to the amount of oil required. The oil will continually pass through the absorbent B into the passage E, thence to the journal bearing. The absorbent can be so compressed that the flow of oil will be at the rate of from one drop a second to one drop an hour, &c. The advantages of our bolster and lubricator, over others now in use, are the regulation of the flow of oil, the saving of both time and oil, and the ease with which the absorbent can be removed when it becomes clogged or gummed.

What we claim as our invention, and desire to secure by Letters Patent, is—

A lubricating bolster, having chamber A, cap C, with or without central perforation, E, and absorbent, B, substantially as described for the purpose set forth.

THOMAS R. ROBINSON,
ROYAL E. JONES.
